MASK

Samuel J. Goldsmith, Chicago, Ill.

Application February 5, 1934, Serial No. 709,690

3 Claims. (Cl. 128—146)

The present invention relates generally to masks for preventing the transmission and contraction of communicable diseases or other infectious matter. More particularly, the invention relates to that type of mask which is adapted primarily for use by physicians, surgeons, nurses and other sick room attendants, operates to filter germs from the air currents running from the nose and mouth of the sick to the wearer and at the same time to prevent germ-laden air and droplets from the nose and mouth of the wearer from reaching the sick, and comprises a textile fabric member which is adapted to fit over and cover the wearer's nose and mouth and has tapes at the sides thereof for encircling the wearer's head and holding the mask in place.

One object of the invention is to provide a mask of this type which is an improvement upon, and is more efficient than, previously designed masks for the same purpose by reason of the fact that it embodies a piece of moisture-proof "Cellophane" which is affixed to one side of, and is coextensive with, the nose and mouth-protecting, textile fabric member, and serves effectively to prevent the passage of air and droplets through the textile fabric member.

Another object of the invention is to provide a mask of the last mentioned character in which the piece of moisture-proof "Cellophane" which forms a facing for one side of the textile fabric member and is coextensive with the latter is connected permanently to, and is in the nature of a lamination of, the member so that it is inseparable from the member and gives the latter the proper or desired stiffness.

Another object of the invention is to provide a mask of the type and character under consideration in which the upper portion of the member having the piece of moisture-proof "Cellophane" laminated thereto is provided with two wedge-shaped infoldments which are stitched at the upper ends thereof to form tucks whereby the upper portion of the member is shaped to conform to the wearer's nose.

Another object of the invention is to provide a mask for the purpose set forth and of the character last mentioned in which the upper portion of the nose and mouth-protecting member is provided with a wire reinforcement which is shaped to bridge the wearer's nose and forms a seal whereby air cannot escape upwardly above the nose where it is likely to becloud eye glasses on the wearer's nose.

Still another object of the invention is to provide a mask in which the nose and mouth-pro-

tecting, textile fabric member has a rounded or convexly curved bottom margin so as to conform generally to the contour of the wearer's chin and is associated with a second member which is connected to the lower portion of, and is formed of the same material as, the nose and mouth-protecting member, and is adapted to underlie the wearer's chin so as to hold the mask in place and to catch any droplets which may accumulate at, or run downwardly to, the bottom margin of the mouth and nose-protecting member.

A further object of the invention is to provide a mask of the aforementioned type in which certain portions of the side parts of the chin-engaging member are cut out to provide openings or spaces at the sides of the mask through which the wearer of the mask may readily breathe without the possibility of disseminating germs.

A still further object of the invention is to provide a mask of the last mentioned character in which the chin-engaging member is stitched to the bottom margin of the nose and mouth-protecting member and the stitched margins of the two members are covered by a tape, the ends of which are extended to and joined to the main mask-holding tape.

Still another object of the invention is to provide a facial mask for use by physicians, surgeons, nurses and other sick room attendants which is generally of an improved construction and may be manufactured at such a low cost that it is practical for the user to use it but once and then throw it away or otherwise dispose of it.

Other objects of the invention and the various advantages and characteristics of the present mask construction will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a perspective showing in its operating position a mask embodying the invention and designed particularly for use by surgeons;

Figure 2 is a side view of the mask of Figure 1;

Figure 3 is a top plan view of the mask showing in detail the position and arrangement of the breathing spaces in the side parts of the chin-engaging member;

Figure 4 is a section on the line 4—4 of Figure 3;

Figure 5 is a perspective of the wire, nose bridge-forming reinforcement in the upper portion of the nose and mouth-protecting member;

Figure 5a is an enlarged detail section showing the manner in which the wire reinforcement is mounted at the upper portion of the nose and mouth-protecting member;

Figure 6 is a perspective of a mask designed primarily for use by nurses and in instances where but limited protection is needed;

Figure 7 is a side view of the mask of Figure 6;

Figure 8 is a rear view; and

Figure 9 is an enlarged vertical section exhibiting the construction and character of the nose and mouth-protecting member and the chin-engaging member, and the manner in which these two members are secured together.

The mask which is shown in Figures 1, 2, 3, 4, 5, and 5a of the drawings and represents one form of the invention is adapted primarily to be used by surgeons although it may, of course, be worn by physicians, dentists, nurses and other sick room attendants or for any desired purpose. It operates to prevent transmission or contraction of communicable diseases or other infectious matters by excluding from the wearer's respiratory tract, germ-laden air running from the nose and mouth of the sick and by preventing germ-laden air and droplets from the wearer's nose and mouth from being transmitted to the sick, that is, the person or persons being treated or attended by the wearer of the mask. The mask is essentially of simple design and consists of a readily flexible, main member 10 for protecting the wearer's nose and mouth and a crescent-shaped, chin-engaging member 11.

The main member 10 is adapted to fit over the wearer's nose, mouth and cheeks, as illustrated in Figures 1 and 2 of the drawings, and is provided with a tape 12 at the upper margin thereof. The upper portion of the member 10 is of greater width than the lower portion so that it not only covers the cheeks but extends almost to the ears. In the center of the upper portion of the member 10, two wedge-shaped infoldments 13 are provided. These infoldments are stitched at the upper ends thereof to form tucks whereby the upper portion of the member 10 is shaped to conform to the nose of the wearer of the mask. The bottom portion of the member 10 is designed so that it extends to the bottom of, and covers, the chin of the wearer of the mask and has a rounded or convexly curved, bottom margin in order that it conforms to the contour of the wearer's chin. The member 10 is formed of readily flexible, compositionally made material which consists of an inner facing 14 of any suitable textile fabric, such as gauze, and an outer facing 15 of moisture-proof "Cellophane". This material is formed by sheeting the facing 15 directly onto a strip of gauze as the "Cellophane" leaves the former heads during manufacture thereof, in order that the facing 15 is permanently attached to the gauze facing 14 throughout the entire area of the contacting or abutting faces thereof. The material is what may be termed "laminated 'Cellophane' and gauze" and is characterized by the fact that the "Cellophane" facing strengthens and gives rigidity to the gauze facing 14. By virtue of the fact that the nose and mouth-protecting member 10 embodies the outer facing 15 of mois-

ture-proof "Cellophane", the mask is non-porous and no germs can pass either inwardly to the respiratory tract of the wearer of the mask or outwardly through the member 10 to the patient being treated by the one wearing the mask. Furthermore, moisture or droplets from the nose or mouth of the wearer of the mask cannot pass through the member 10. Because of the absorptive property of the inner facing 14 of gauze, all droplets from the wearer's nose and mouth are absorbed by the inner facing and hence infectious matter is prevented by the mask from being transmitted from the wearer of the mask to the person being treated by the mask wearer. By employing a gauze inner facing, the mask is extremely comfortable to the wearer. The tape 12 is formed of any suitable textile fabric and is preferably folded upon itself in a lengthwise direction so that it is of double thickness. It is coextensive with the top margin of the member 10 and is connected to the latter by stitching 16. In attaching the tape 12 to the upper portion of the nose and mouth-protecting member 10 of the mask, the tape is folded around the top margin of the member 10 and then the stitching 16 is formed so that the loops thereof pass through the tape and the top margin of the member 11.

In order to reinforce the member 10 and at the same time to form a nose bridge for holding the mask in place, a wire 17 is disposed in the channel or space between the folded portions of the tape 12 (see Figure 5a). This wire is coextensive with the upper portion of the member 10 and has the central portion thereof bent into the form of an arch or bridge for nose engaging purposes. The bridge-forming portion of the wire is adapted when in its operative position on the nose of the wearer of the mask to assist in holding the mask in place and to form a seal whereby the breath of the mask wearer cannot pass upwardly into the wearer's eyes or around glasses on the wearer's nose where it might becloud such glasses. The ends of the wire 17 terminate at the end portions of the member 10 and serve as a reinforcement for the mask. The wire is formed of readily bendable metal so that the nose bridge portion may be bent to fit noses of different shapes.

The chin-engaging member 11 is formed of the same material as the nose and mouth-protecting member 10 and consists of an inner facing 18 of gauze and an outer facing 19 of moisture-proof "Cellophane". The outer facing of "Cellophane" is permanently united to the gauze facing 18 throughout the entire area of the contacting faces thereof and renders the member 11 moisture-proof. The member 11 is adapted to underlie the chin of the wearer of the mask as shown in Figure 2 of the drawings, and has the front margin thereof curved substantially conformably to the bottom margin of the member 10 and united to the latter by stitching 20. A pocket 21 is formed between the members 10 and 11 and this pocket is so shaped because of the curvature or roundness of the stitched margins of the two members, that it fits the chin of the wearer of the mask in a snug fashion. In the event of accumulation of moisture or droplets in the pocket, such moisture and droplets are absorbed by the gauze inner facing 18 of the member 11. When the mask is not in use, the member 11 assumes the position shown in Figure 4 of the drawings. When the chin-engaging member 11 is in this position, the mask occupies but a small amount

of space and may be readily stacked with other masks of like character.

5 To provide for ready breathing of the wearer of the mask, the side portions of the chin-engaging member 11 are cut away to form a pair of openings 22. These openings are located in the margin of the member 11 which is stitched to the bottom margin of the members 10, and are so positioned that the wearer's breath is directed 10 laterally.

10 A tape 23 serves to support the mask in its operative position. The central portion of this tape is folded in a lengthwise direction around the contacting or contiguous margins of the members 10 and 11, as shown in Figure 4, and is secured in place by means of the stitching 20. In forming the mask, the member 11 is placed on the member 10 so that the inner facing 18 abuts against the gauze facing 14 of the member 10 15 and the two curved margins of the members coincide. Thereafter, the central portion of the tape 23 is folded lengthwise around the rounded margins of the two members and the stitching 20 is formed by passing the loops thereof through the tape and the two members. The ends of the tape 22 are sufficiently long so that they may be placed over the ears of the wearer of the mask and then tied around the back of the wearer's head. When the ends of the tape 23 are tied together in this manner, the members 10 and 11 20 are held in their proper positions.

25 In applying the mask, the chin-engaging member 11 is first swung away from the member 10 in order to open the pocket 21. Thereafter, the chin-engaging member is placed under the wearer's chin and the member 10 is swung into place over and across the mouth and lower portion of the nose. After the members 10 and 11 are 30 properly positioned, the arch or bridge part of the wire 17 is moved inwardly so that the user's nose is securely gripped. After this is done, the ends of the tape 23 are passed over the wearer's ears and behind the head and are then tied in order to hold the mask in place. When the mask is in place, the openings 22 provide for breathing 35 but do not allow the breath of the wearer of the mask to flow downwardly. All moisture and droplets are absorbed or caught by the gauze inner facings of the members 10 and 11, as heretofore pointed out, and the respiratory tract of the wearer of the mask is protected against germs by way of the outer facings 15 and 19 of moisture-proof "Cellophane".

40 The mask which is shown in Figures 6, 7, 8, and 9 and represents another form of the invention is 45 adapted primarily for use by nurses and other sick room attendants, and comprises a readily flexible main member 110 and a chin-engaging member 111. The upper portion of the member 110 is of less width than the lower portion and has downwardly divergent side edges which are normally spaced from the wearer's cheeks a sufficient distance to permit of ready breathing of the wearer of the mask. The member 5 is formed of 50 composite material and consists of an inner facing 114 and an outer facing 115 of moisture-proof "Cellophane". The inner facing is formed of Canton flannel instead of gauze as in the case of the inner facing 14 of the mask of Figures 1, 2, 3, 55 4, 5, and 5a, and the outer facing 115 of "Cellophane" is permanently attached to the inner facing as in the case of the outer facing 15 of the member 10 of the mask first described. The chin-engaging member 111 is formed of the same material as the main member 110 and forms a pocket 60

65 121 for receiving the wearer's chin. The contacting or contiguous margins of the members 110 and 111 are secured together by means of stitching 120 and a tape 123. The central portion of this tape is secured to the bottom portion of the main member 110 by means of the stitching 120 and the ends extend upwardly and are connected in any suitable manner to a tape 112. The latter has the central portion thereof stitched to the upper portion of the main member 110 and the 70 ends thereof are extended so as to form the supporting medium or instrumental for the mask. The ends of the tape 123 are joined or connected to the ends of the tape 112 at points between the extreme end parts of the tape 112 and the upper 75 portion of the member 110. By so connecting the ends of the tape 123, the lower portion of the main member 110 as well as the chin-engaging member 111, is held in place when the ends of the tape 112 are tied around the back of the head 20 of the wearer of the mask. A wire 117 is confined in the central portion of the tape 112 which is applied to the upper portion of the main member 110 and is arched so as to form a nose bridge for the mask. This bridge, like the bridge of the 25 mask of Figures 1, 2, 3, 4, 5, and 5a, forms a seal whereby the breath of the wearer of the mask is precluded from passing upwardly.

30 The mask of Figures 6, 7, 8, and 9 is applied similarly to the first described mask and operates to prevent transmission or contraction of communicable diseases or other infectious matters by excluding from the wearer's respiratory tract germ-laden air running from the nose and mouth of the sick and by preventing germ-laden 35 air and droplets from the wearer's nose and mouth from being transmitted to the sick, that is, the person or persons being treated or attended by the wearer of the mask. Because of the absorptive properties of the Canton flannel which 40 is used to form the inner facings of the main member 110 and the chin-engaging member 111, all droplets or moisture from the wearer's nose and mouth are absorbed and hence precluded from leaving the mask.

45 The herein described mask constructions are exceedingly efficient in operation and may be manufactured at such a low cost that it is practical for the wearers of the masks to use the latter but once and then to throw them away or 50 otherwise dispose of them.

55 The invention is not to be understood as restricted to the details set forth, since these may be modified within the scope of the appended claims, without departing from the spirit and 55 scope of the invention.

Having thus described the invention, what I claim as new and desire to secure by Letters Patent, is:

1. As a new article of manufacture, a mask 60 comprising a readily flexible member adapted to cover the wearer's nose and mouth and consisting of inner and outer, coextensive, abutting facings formed respectively of textile fabric and moisture-proof "Cellophane" and united permanently 65 together throughout the entire contracting area thereof, and means for supporting the member in its operative position.

2. As a new article of manufacture, a mask 70 comprising a readily flexible, main member adapted to cover the wearer's nose and mouth and formed of inner and outer coextensive, abutting facings formed respectively of textile fabric and "Cellophane" type material and united permanently 75 together throughout their entire contact-

ing area, a separately formed second member of flexible, moisture absorbing material adapted to underlie the wearer's chin and having the front margin thereof secured to the bottom margin of 5 the main member, and tape means for securing the two members in their operative position.

3. As a new article of manufacture, a mask comprising a readily flexible, main member adapted to cover the wearer's nose and mouth and 10 having a rounded bottom margin corresponding generally to the contour of the wearer's chin and formed of inner and outer, coextensive, abutting facings formed respectively of textile fabric and

moisture-proof "Cellophane" and united permanently together throughout their entire contacting area, a separately formed, readily flexible, crescent shaped member of the same material as the main member adapted to underlie the 5 wearer's chin and having the convex margin thereof coextensive with and corresponding in shape to said rounded bottom margin and fitting flatly against and stitched to the latter, and tape means for securing the two members in their 10 operative position.

SAMUEL J. GOLDSMITH.
